WITNESS:

UNITED STATES PATENT OFFICE.

MURRAY R. BODINE AND SYLVESTER B. DUNLAP, OF MUNCY, PENNSYLVANIA.

TOY.

1,402,563.

Specification of Letters Patent. Patented Jan. 3, 1922.

Application filed February 17, 1920. Serial No. 359,289.

To all whom it may concern:

Be it known that we, MURRAY R. BODINE and SYLVESTER B. DUNLAP, citizens of the United States, residing at Muncy, in the county of Lycoming, and State of Pennsylvania, have invented new and useful Improvements in Toys, of which the following is a specification.

This invention relates to a novel construction of toy and the principal object of the invention is to provide a zigzag run-way for marbles, balls and the like with means associated with the run-way for causing the marbles to actuate bell mechanism as they pass along the run-way.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a side view of the device.

Figure 2 is a plan view.

Figure 3 is a section on line 3—3 of Figure 1.

In these views 1 indicates a base which is provided with a flange 2 to form a tray. A pair of posts 3 are supported on the base and a zigzag runway 4 is supported by said posts. As shown this run-way is formed of a number of strips 5 which are of trough-shape in cross section. The strips are located one above the other and the lower end of each strip is provided with a hole 6 for permitting the marbles to drop therethrough on to the strip beneath. In this way the marbles placed in the upper strip will travel along the run-way under the action of gravity and finally drop into the tray. The marbles may then be picked up and placed in the upper strip so that they will again travel along the run-way.

A bell, or bells, 7 is secured to the under-

side of the strip and the hammer 8 of the bell is pivoted in said strip with one end passing through a slot 9 formed in the bottom of the strip. This hammer is normally held in a vertical position due to the action of gravity with its upper end extending into the run-way where it will be struck by the marbles as they pass along the run-way. Thus as the marbles strike this upwardly extending end the hammer will be rocked to cause its lower end to strike the bell and sound the same. As soon as the marble passes the hammer will assume its normal vertical position.

It will of course be understood that we may use a plurality of these bells and hammers and place them on one strip or on all the strips. We prefer to make the bells of different sizes so as to give the effect of chimes or the like.

It is thought from the foregoing description that the advantages and novel features of my invention will be readily apparent.

We desire it to be understood that we may make changes in the construction and in the combination and arrangement of the several parts, provided that such changes fall within the scope of the appended claim.

What we claim is:—

A toy of the class described comprising a base having a flange around its edge to form a tray, a pair of posts supported on the base adjacent the ends thereof, a number of strips having their ends connected with the posts, said strips being inclinedly arranged and placed one above the other and being of trough shape in cross section to form a runway and each strip having a hole adjacent one end for permitting a ball to drop therethrough, a bell secured to the lower face of one strip and a hammer pivotally mounted on said strip adjacent the bell and having a part projecting into the trough.

In testimony whereof we affix our signatures.

MURRAY R. BODINE.
SYLVESTER B. DUNLAP.
